US00D978953S

(12) **United States Design Patent** (10) Patent No.: **US D978,953 S**
(45) Date of Patent: **** Feb. 21, 2023**

(54) **CAMERA HOUSING**

- (71) Applicant: **GoPro, Inc.**, San Mateo, CA (US)
(72) Inventors: **Daniel J. Coster**, Oakura (NZ); **Bessy Liang**, San Jose, CA (US); **Huy Phuong Nguyen**, Alpine, UT (US); **John George Muhlenkamp, IV**, Brisbane, CA (US); **Jordan Todd**, Piedmont, CA (US)
(73) Assignee: **GoPro, Inc.**, San Mateo, CA (US)
(**) Term: **15 Years**
(21) Appl. No.: **29/842,487**
(22) Filed: **Jun. 14, 2022**

Related U.S. Application Data

- (60) Continuation of application No. 29/805,978, filed on Aug. 31, 2021, now Pat. No. Des. 957,503, which is

(57) **CLAIM**

The ornamental design for a camera housing, as shown and described.

DESCRIPTION

FIG. 1 is a top, front, and right side perspective view of a camera housing showing our new design;
FIG. 2 is a bottom, rear, and right side perspective view thereof;
FIG. 3 is a top, rear, and left side perspective view thereof;
FIG. 4 is a front elevation view thereof;
FIG. 5 is a rear elevation view thereof;
FIG. 6 is a left elevation view thereof;
FIG. 7 is a right elevation view thereof;
FIG. 8 is a top plan view thereof; and,
FIG. 9 is a bottom plan view thereof.

The broken lines depict portions of the camera housing in which the design is embodied that form no part of the claimed design. Additionally, the broken lines showing a camera within the camera housing in FIGS. 1–9 represent environmental structure and form no part of the claimed design.

1 Claim, 8 Drawing Sheets

Related U.S. Application Data

a division of application No. 29/771,317, filed on Feb. 22, 2021, now Pat. No. Des. 929,489, which is a division of application No. 29/705,667, filed on Sep. 13, 2019, now Pat. No. Des. 911,411.
